(57) **CLAIM**

The ornamental design for a minor, as shown and described.

DESCRIPTION

FIG. 1 is a perspective view of a minor showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view thereof in a closed configuration.

FIG. 10 is an enlarged view of portion 10 shown in FIG. 2; and,

FIG. 11 is an enlarged view of portion 11 shown in FIG. 3. The dash-dash broken lines in the drawings depict portions of the mirror that form no part of the claimed design. The long-dash short-dash broken lines represent the boundaries of the enlarged portions and form no part of the claimed design.

1 Claim, 11 Drawing Sheets
